Primary Examiner—Carol Rademaker(57) **CLAIM**

The ornamental design for a nail polish bottle, as shown and described.

DESCRIPTION

FIG. 1 is a front elevational view of a nail polish bottle showing my new design, the rear elevational view being a mirror image thereof;

FIG. 2 is a side view, taken from the left side of FIG. 1, the right side view being a mirror image thereof;

FIG. 3 is a top plan view thereof; and,

FIG. 4 is a bottom plan view thereof.

1 Claim, 2 Drawing Sheets**FIG. 1**

FIG. 2

FIG. 3

FIG. 4
